HIGH TEMPERATURE, SHORT CONTACT-TIME PYROLYSIS OF DICHLORODIFLUOROMETHANE

John Richard Soulé, Narberth, and William Ford Schwartz, King of Prussia, Pa., assignors to Pennsalt Chemicals Corporation, Philadelphia, Pa., a corporation of Pennsylvania
 No Drawing. Filed Oct. 18, 1965, Ser. No. 497,535
 6 Claims. (Cl. 260—653)

ABSTRACT OF THE DISCLOSURE

Dichlorodifluoromethane (CCl_2CF_2) is pyrolyzed at a temperature within the range of about 1100° C . to about 2000° C . for a period of from 0.0002 to 0.05 second to produce, as a major product, 1,2-dichlorotetrafluoroethane ($\text{CClF}_2\text{CClF}_2$).

This invention relates to the preparation of other organic fluorochloro compounds by the pyrolysis of dichlorodifluoromethane. More particularly, this invention concerns pyrolyzing dichlorodifluoromethane (CCl_2F_2) to produce as the major products, primarily, 1,2-dichlorotetrafluoroethane ($\text{CClF}_2\text{CClF}_2$), and secondarily, chlorotrifluoromethane (CClF_3). By "pyrolysis" is meant the transformation of a compound into another compound or other compounds through the agency of heat alone, and therefore the term includes not only the rearrangement of a compound but also the making of more complex compounds.

A. B. Trenwith and R. H. Watson, J. Chem. Soc., 1957, pp. 2368-2372, describe the pyrolysis of CCl_2F_2 at a temperature ranging from 700° C . to 900° C ., whereby the principal products were CClF_3 and chlorine, and smaller amounts of CCl_3F and CCl_4 were obtained as minor products. Dichlorotetrafluoroethane was detected in merely a trace amount in the reaction products only from the pyrolysis at 750° C . F. B. Downing, A. F. Benning and R. C. McHarness, U.S. Patent No. 2,551,573, pyrolyzed CCl_2F_2 at 950 to 970° C . and obtained as the reaction products CF_4 and CF_3Cl ; however, no $\text{CClF}_2\text{CClF}_2$ was produced by this method.

It has now been discovered that high temperature pyrolysis of CCl_2F_2 , i.e., in the range of about 1100° C . to about 2000° C ., unexpectedly produces $\text{CClF}_2\text{CClF}_2$ in relatively high yield as a principal reaction product, CClF_3 as a major product of secondary importance, and as minor products, CCl_3F , $\text{CCl}_2\text{FCCl}_2\text{F}$ and $\text{CCl}_2\text{FCClF}_2$. However, the time of the pyrolysis reaction embodied herein is very short and should not exceed about 0.05 second. Thus, a principal product of the pyrolysis of CCl_2F_2 embodied in this invention is a haloethane although the principal products of the pyrolyses of CCl_2F_2 using prior art processes are halomethanes. The most desired product of the process of this invention, $\text{CClF}_2\text{CClF}_2$, is a valuable refrigerant used mainly in systems having centrifugal rotary compressors. The product CClF_3 is valuable as a refrigerant for ultralow temperatures. The minor products are also useful as well known refrigerants. Moreover, CClF_3 and CCl_3F can be pyrolyzed at high temperatures to produce additional $\text{CClF}_2\text{CClF}_2$ as described in our copending applications, Ser. No. 499,084, filed Oct. 20, 1965 and Ser. No. 495,348, filed Oct. 12, 1965, respectively.

As stated above, the pyrolysis of CCl_2F_2 is carried out according to this invention at a temperature within the range of about 1100° C . to about 2000° C . The preferred

temperature range with regard to obtaining the highest conversion of the CCl_2F_2 and highest yields of

therefrom is from about 1400° C . to about 1800° C . As earlier stated, in combination with the high pyrolysis temperatures used in the practice of this invention, very short contact times of the CCl_2F_2 at such temperatures are employed, that is, pyrolysis times on the order of about 0.0002 to 0.05 second, preferably in the range of about 0.0006 to about 0.01 second. At contact times of the usual order of magnitude used in pyrolyses of this type, i.e., on the order of about 10 seconds and higher, the process of this invention is inoperative because of considerable degradation of the reactant and reaction products. As used herein contact time is defined as follows:

$$\text{Contact time (seconds)} = \frac{\text{heated reactor volume}}{\text{volume of gas per second (calculated at reaction temperature and pressure) fed to reactor.}}$$

The short contact times indicated above for the pyrolysis of this invention correspond to very high space velocities ranging from about 500 to about 120,000 per hour which permit a high rate of feed and reduce reactor volume needed. Space velocity is defined as volumes of reactant (measured at standard temperature and pressure (STP), i.e., 0° C . and 760 mm. Hg) per volume of heated reactor per hour. This is in sharp contrast to the much lower space velocities previously employed in the pyrolyses of CCl_2F_2 , on the order of about 6 to 75 per hour. For example, A. B. Trenwith and R. H. Watson, Journal of Chemical Society, ibid, used extended reaction times of about 145 to 175 seconds for pyrolyzing CCl_2F_2 , and in the above-mentioned U.S. Patent No. 2,551,573, pyrolysis times on the order of about 11 seconds were used (Example XXIII).

The reaction pressure in the present process is not critical and may be atmospheric, sub-atmospheric or super-atmospheric. Super-atmospheric pressures may range, e.g., up to about 10 atmospheres. However, atmospheric and sub-atmospheric pressure operation will generally be found most convenient. As a practical matter, pressures lower than about one mm. Hg absolute are not recommended. Preferred operating pressures will generally range from about 10 mm. Hg to atmospheric pressure.

The pyrolysis is conveniently carried out by continuously passing a stream of the CCl_2F_2 feed through an elongated tube preferably having a high ratio of wall area to cross-sectional area so that heat may be rapidly and continuously transferred from the heated reactor wall to the gaseous reactant. The reactor should be constructed of a material resistant to attack by the reactant and reaction products at the high operating temperatures. Materials of this type include, for example, inert graphite, boron nitride and like inert materials. The reactor can be heated to the desired pyrolysis temperatures in any suitable manner such as by electrical induction heating or by placing the reactor in an electrically heated furnace.

The products of the pyrolysis reaction passing from the reactor are cooled and usually will be scrubbed in caustic solution or other alkaline solution to remove acidic, inorganic by-products (e.g., chlorine and fluorine). The organic products are separated from the reaction mixture in the conventional manner by fractional distillation. The unreacted CCl_2F_2 can, of course, be recovered for recycling purposes.

Examples 1-6

In the experiments herein described, specific embodiments of the invention are set forth to illustrate and clarify the invention.

Gaseous CCl_2F_2 is passed continuously at a measured rate through a $\frac{1}{8}$ inch I.D. x $\frac{1}{2}$ O.D. x 13" long, inert graphite tube reactor centered within a 2" diameter "Vycor" high-silica glass tube, 15 inches long. The reactor is inductively heated with a 3 $\frac{1}{4}$ " long load coil of 12 turns of $\frac{1}{4}$ inch copper tubing about the "Vycor" tube, the power for said coil supplied by a high frequency generator with a maximum output of 7.5 kilowatts operating at 450 kilocycles. The effective reaction zone in the tube is thus 3 $\frac{1}{4}$ inches. The temperature of the reactor is measured with an optical pyrometer focused on the center of the heated portion of the tube. Examination of the inert graphite reactor after repeated runs therein reveals that its inner surface is unaffected by the passage of the hot gases therethrough.

The product mixture passes from the reactor and is condensed in a trap cooled with liquid nitrogen. The condenser is vented to a mechanical vacuum pump which maintains the sub-atmospheric reaction pressure employed in these examples. After completion of the run, the reaction products are warmed to room temperature and transferred to an evacuated stainless steel cylinder. The reaction products are then passed through a series of scrubbers containing aqueous solutions of sodium hydroxide to remove the inorganic by-products. The organic reaction products are analyzed using gas-liquid chromatographic and infrared analyses techniques.

The data from six runs are summarized in Table I. In addition to the components listed in the "Product" column of Table I, the reaction products contain unreacted CCl_2F_2 and varying minor amounts of CF_4 , CCl_4 ,

$\text{CClF}=\text{CClF}$, and CCl_2FCF_3 , an isomer of the desired product, $\text{CCClF}_2\text{ClF}_2$.

reaction. The principal reaction products are $\text{CClF}_2\text{CClF}_2$ (20 weight percent), CClF_3 (63%) and CF_4 (17%).

It is to be understood that the foregoing illustrative examples should not be construed as limitative of the scope of the invention which is defined by the appended claims.

We claim:

1. The method which comprises pyrolyzing dichlorodifluoromethane at a temperature of from about 1100° C. to about 2000° C., wherein the pyrolysis time is from about 0.0002 to about 0.05 second, a major product of the pyrolysis being 1,2-dichlorotetrafluoroethane.

2. The method of claim 1 wherein the pyrolysis temperature is from 1400° C. to about 1800° C.

3. The method of claim 1 wherein the pyrolysis time is from about 0.0006 to about 0.01 second.

4. The method which comprises pyrolyzing dichlorodifluoromethane at a temperature of from about 1400 to 1800° C. wherein the pyrolysis time is from about 0.0006 to 0.01 second, a major product of the pyrolysis being 1,2-dichlorotetrafluoroethane.

5. The method of pyrolyzing dichlorodifluoromethane which comprises passing dichlorodifluoromethane through a tube heated to a temperature of from about 1100° C. to about 2000° C., wherein the contact time is within the range of about 0.0002 to 0.05 second, a major product of the pyrolysis being 1,2-dichlorotetrafluoroethane.

6. The method of pyrolyzing dichlorodifluoromethane which comprises passing dichlorodifluoromethane through a tube heated to a temperature of from about 1400° C. to about 1800° C., wherein the contact time is within the range of about 0.0006 to 0.01 second, a major product of the pyrolysis being 1,2-dichlorotetrafluoroethane.

TABLE I

Example	Pyrolysis Conditions				Percent conversion of CCl_2F_2	Weight Percent in Recovered Converted Product of—				
	Feed rate of CCl_2F_2 , gms./min.	Pressure, mm. Hg abs.	Temp., °C.	Contact time, seconds		$\text{CClF}_2\text{CClF}_2$	CClF_3	CCl_3F	$\text{CCl}_2\text{FCCl}_2\text{F}$	$\text{CCl}_2\text{FCClF}_2$
1-----	1.057	29	1,130	0.0013	4.7	71.7	8.7	4.9	Nil	3.4

Example 7

The procedure of the preceding examples is repeated using an 80% platinum-20% rhodium alloy tube as the pyrolysis reactor. The pyrolysis temperature is about 1500° C., the pressure is 26 mm. Hg and the contact time is 0.003 second (space velocity=7040 per hour). 24 percent of the CCl_2F_2 fed is converted via the pyrolysis
